Des. 187,805
Patented May 3, 1960

187,805

TOY AUTOMOTIVE VEHICLE

Allan J. Alvaney, Arlington Heights, Ill., assignor to Sears, Roebuck and Co., Chicago, Ill., a corporation of New York

Application June 15, 1959, Serial No. 56,356

Term of patent 14 years

(Cl. D34—15)

Fig. 1.

Fig. 2.

Fig. 1 is a front-side perspective view of a toy automotive vehicle; and

Fig. 2 is a rear perspective view of same showing the opposite side.

The dominant feature of my design resides in the portion shown in full lines.

I claim:

The ornamental design for a toy automotive vehicle, as shown and described.
